ABSTRACT: A device for controlling AC flowing through a load by means of an AC thyristor which is triggered through a trigger control network arrangement comprising an AC diode and a network arrangement known per se which functions as a bilateral transistor. In order to obtain an automatic compensation for inequalities of the transistors used in the aforesaid network arrangement, and also in order to extend the range over which the AC current value can be controlled, a capacitor is included between said AC diode and said network arrangement known per se.

ALTERNATING CURRENT CONTROL DEVICE

The invention relates to an alternating current control device having one or more inputs for manual and/or automatic control of the r.m.s. value of the current.

It is known to control the r.m.s. value of alternating current flowing through a given load by means of a triode AC semiconductor switching element (AC thyristor, Triac), which is series connected with said load and connected to the AC main supply. As a rule the ignition of the Triac is effectuated by means of a diode AC semiconductor switching element (diac), which is connected to the gate of the triac and which is fed from an RC network which is connected across the triac.

FIG. 1 shows the most simple embodiment of such known circuit arrangement. The triac T is series connected with the load L across the AC supply. The diac D is fed from the capacitor C₁, which is charged through the resistor R₁. These last mentioned components are series connected to each other and are connected across the triac. According to the prior art a second RC combination R₂C₂ can be added, which combination is coupled to the junction of the first RC combination R₁C₁ via the resistor R₃, in order to improve the stability during the start of this ignition device and in order to prevent a hysteresis effect during said start. Reference is made to a transistor publication about triacs (see General Electric SCR Manual, 4th edition). The ignition can be controlled by adjusting the resistors R₁, R₂ and/or R₃. It is also possible to shunt one of the capacitors C₁ or C₂ with a control resistor and to delay by means thereof the charging of C₁ or C₂ and consequently to delay the ignition moment. For an automatic control a photosensitive resistor (LDR) may be used which has a very high dark resistance and very low light resistance.

If control elements are used which produce a lower variation in resistance than an LDR, this known circuit arrangement is not sensitive enough to effect an automatic control over the full sine wave. For instance a temperature dependent NTC or PTC resistor merely gives a variation of the resistance of 1:2 when temperature varies over a very large range. Then for said circuit arrangement this is much too small a variation for effecting a complete control from zero to full current.

The invention provides a circuit arrangement which provides an extremely sensitive input for said control device and wherein with a NTC resistor across said input a temperature sensitivity with an accuracy of 1°C. is produced. Said circuit arrangement does not need an adjustment because it comprises an automatic compensating control of the semiconductors used.

FIG. 2a shows an embodiment of a triode AC control device comprising two branches each composed of a transistor and a diode, these diodes being poled for conducting currents of opposite directions, and wherein the bases of the transistors are interconnected. The device functions as a bilateral transistor and is very well suitable for an integrated structure. In that latter case, however, the large chance should be taken into account that the NPN and PNP transistor will have unequal properties (gain factors and the like). According to the invention provisions should be made to this effect.

FIG. 2b shows an alternative of the circuit arrangement according to FIG. 2a to which two diodes D₃ and D₄ which provide a Zener-effect during the starting period, are added.

FIG. 2c shows a further alternative comprising the Zener-diodes Z₁ and Z₂ in the emitter leads in order to obtain the same effect to a higher degree. However, as a rule, this circuit arrangement is more expensive and it is still more difficult to obtain equal operation as to the left-hand branch and in the right-hand branch.

Therefore the simple embodiment of FIG. 2a is to be preferred.

FIG. 3 shows an application of the circuit arrangement according to FIG. 1: the triode control device TR is connected across the capacitor C₁ and its control terminal is connected

to the upper end of a voltage divider R₄R₅, which is also connected across the capacitor C₁. By varying one of the resistors R₄ or R₅, the charging rate of the capacitor C₁ will be changed, so that also the ignition moment is shifted. However, the sensitivity for said variation is very large, so that now one of the resistors R₄ or R₅ can be dimensioned as a NTC resistor while the other may be used for effecting as a preliminary adjustment by hand. Then the temperature sensitivity is very high and renders a temperature control within 1°C. amply possible. However, automatic control over a range extending over the full sine wave cannot be achieved with this circuit arrangement.

As already stated inequality of the transistors T₁ and T₂ in the control device TR also an inequality in the shifting of the ignition moment. This is a serious deficiency, especially when control of AC motors, more in particular AC fans having a short circuited armature, is concerned.

According to the invention a surprising solution to the above-mentioned problems is obtained by connecting a capacitor in series with the control device TR and the voltage divider connected in parallel thereto; thereby an automatic compensation for the above indicated inequality is achieved, while moreover the control range is caused to extend over the full sine wave. FIG. 4 shows a circuit arrangement wherein this solution is incorporated.

The capacitor C₃ is series connected with the control device TR and the voltage divider R₄R₅ connected in parallel thereto. The operation is as follows:

If at a predetermined adjustment of the voltage divider R₄R₅ the control device TR will become conductive during a positive voltage period, the capacitor C₃ is charged. The voltage produced across the capacitor C₃ each time that capacitor is charged during a half cycle, is maintained during the following half cycle until the control device becomes conductive again. The voltage thus maintained, by its value is representative of the point of time at which the triac T was triggered into conduction during the previous half cycle. This voltage across capacitor C₃ has the effect of compensating inequalities in the two branches included in the control device TR, in the sense that the voltage maintained across C₃ in combination with the voltage developed across capacitor C₁ is effective to trigger the triac T into conduction at the same point of time relative to the beginning of the half cycles. This circuit arrangement according to the invention produces a surprising compensation with regard to unequal semiconductors in the control device TR. This is of considerable importance in case TR is an integrated structure, which is extremely difficult to dimension with equal branches, particularly in regard to the transistors and such can only be obtained by selection. Owing to this the cost price is substantially increased.

The use of the resistor R₆ between the voltage divider R₄R₅ and the RC member R₂C₂, advances the operation of the control device TR and makes the circuit arrangement still more sensitive.

FIG. 5 shows the same circuit arrangement wherein the control device TR is reversed. In that case variation of the resistors R₄ and R₅ produces a shift of the ignition moment which is opposite relative to that of the arrangement according to FIG. 4.

FIG. 6 shows how the embodiment of FIG. 4 can be arranged for an inductive load L; following parts are added: the well-known RC combination R₇C₄ serving to prevent oscillations of the triac T, the filter comprising the choke coil S and the capacitor C₅ and if desired the capacitor C₆ effective to eliminate undesired interfering pulses occurring on the main voltage supply and in order to improve the load impedance presented to the main voltage supply.

If the resistor R₅ is dimensioned as a remote control element it is desirable according to the invention to directly connect the O-conductor with the resistor R₅ and consequently not to include a choke coil in said conductor. When using longer conductors at R₅, they will consequently not radiate. When using a long O-conductor, the O-connection of the circuit arrangement may be earthed through a capacitor, if desired.

A same arrangement of FIG. 5 then results in corresponding possibilities, wherein the control of R_5 produces a reversed effect. This is important for an automatic temperature control with heating elements. Although in the case of heating elements an equal ignition in - and + direction is less essential, also here the capacitor C_3 is important for obtaining a balanced load of the AC main supply, for which feature the administrations of power plans show an increasing interest now that thyristors and triacs are used more and more.

When using the circuit arrangement shown in FIG. 6 for the automatic control of AC fans, it may be desirable to have a minimum control and in some cases also a maximum control at one's disposal. Such control operations can be obtained in a well-known manner by providing a second diac ignition network, wherein the diac discharges itself on the same triac.

The maximum control is obtained in a simple manner varying one of the resistors R_1 , R_2 or R_3 . Such an embodiment is shown in FIG. 7. A second ignition diac D_4 is fed from the RC-member R_8C_7 and if desired stabilized by the RC-member R_9C_8 , which is coupled thereto through the resistor R_{10} . According to the invention the taking over of the ignition by the second diac is substantially improved by means of the coupling resistors R_{11} and R_{12} which strongly suppress the hysteresis effect occurring during said taking over.

Instead of the control resistors other control elements may also be used, provided the resistance thereof will vary sufficiently in order to fully excite the control device.

The portion at the right-hand side of the broken line drawn in the figures is in particular effective to improve the start of the control process; however, this part is not essential for the further control range. The resistor R_6 provides an improvement of the input sensitivity.

The operative voltage of the resistor R_5 is very low and has as its maximum value the emitter-base voltage surge of the silicon transistors which are preferably used. Consequently there is practically no loss of energy in this control resistor, this contrary to other circuit arrangements in this field. This is important when using very small control resistors having a slight heat capacity, which here are substantially not heated.

Although the reliability in operation thereof is not yet entirely understood in the meantime high voltage diode AC semiconductor switching elements have been put on the market which can be ignited by means of igniting coils, wherein the ignition device up to the ignition coil may be arranged in analogy to a triac-ignition device.

Obviously when triacs are mentioned above they may be replaced by the above mentioned combination of diode switching elements comprising an ignition coil (See Electronics World, May 1965, page 42, FIG. 1/I).

I claim:

1. An alternating current control device comprising a triode

- AC semiconductor switching element (triac T), having a gate, series connected to a load, an ignition device having a resistor-capacitor circuit R_1C_1 which is connected in parallel to said triode AC semiconductor switching element T and includes a first resistor R_1 and a first capacitor C_1 , a junction between said first resistor R_1 and said first capacitor C_1 being connected to the gate of the said triode AC semiconductor switching element T via a diode AC semiconductor switching element (diac D) characterized in that a second capacitor C_3 is included between said junction of said first resistor R_1 and said first capacitor C_1 and a control circuit arrangement TR, the control input terminal of which is connected to a tapping of a voltage divider R_4R_5 which is connected in parallel to said control circuit arrangement TR.
- 10 2. An alternating current control device according to claim 1, wherein a second RC circuit R_2C_2 including a second resistor R_2 and a third capacitor C_2 is connected in parallel to said triode AC semiconductor switching element T and said junction between said first resistor R_1 and said second capacitor C_1 is connected to a junction of said second resistor R_2 and said third capacitor C_2 , via a third resistor R_3 , said tapping of the said voltage divider R_4R_5 being connected to said junction between said second resistor R_2 and said third capacitor C_2 , via a fourth resistor R_6 .
- 15 3. An alternating current control device according to claim 2, wherein said fourth resistor is variable.
4. An alternating current control device according to claim 2, wherein said voltage divider R_4R_5 is adjustable.
5. An alternating current control device according to claim 30 3, wherein said voltage divider R_4R_5 is adjustable.
6. An alternating current control device according to claim 1, wherein said voltage divider R_4R_5 includes a plurality of resistors, at least one of which is adjustable.
7. An alternating current control device according to claim 35 2, wherein said voltage divider R_4R_5 includes a plurality of resistors, at least one of which is adjustable.
8. An alternating current control device according to claim 3, wherein said voltage divider R_4R_5 includes a plurality of resistors, at least one of which is adjustable.
9. An alternating current control device according to claim 40 4, wherein said voltage divider R_4R_5 includes a plurality of resistors, at least one of which is adjustable.
10. An alternating current control device according to claim 45 1, wherein said voltage divider R_4R_5 includes a plurality of resistors, at least one of which is a temperature sensitive resistor.
11. An alternating current control device according to claim 2, wherein said voltage divider R_4R_5 includes a plurality of resistors, at least one of which is a temperature sensitive resistor.
